UNITED STATES PATENT OFFICE.

EDWARD G. COLLINS, OF KENESAW, NEBRASKA.

COMBINED HAND-TRUCK AND WEIGHING-SCALE.

SPECIFICATION forming part of Letters Patent No. 391,453, dated October 23, 1883.

Application filed March 15, 1883. Serial No. 267,928. (No model.)

To all whom it may concern.

Be it known that I, EDWARD G. COLLINS, of Kenesaw, in the county of Adams and State of Nebraska, have invented certain new and useful Improvements in a Combined Hand-Truck and Weighing-Scale; and I do hereby declare the following to be a full, clear, and exact description of the invention, such as will enable others skilled in the art to which it appertains to make and use the same.

My invention relates to an improvement in a combined hand-truck and weighing-scale.

On July 19, 1887, Letters Patent No. 366,753 were issued to Albert A. Armitage, entitled "combined hand-trucks and weighing-scales." In said Letters Patent a support was provided with a system of levers on which the truck-body was adapted to rest when the latter assumed a horizontal position, and a weight-indicating device was so connected with the system of levers that the weight of anything placed upon the platform of the truck could be determined.

The object of my present invention is to so 25 simplify, construct, and arrange the several parts of the combined truck and weighing-scale as to render its manufacture and use eminently practicable, and to increase its efficiency as a truck and its reliability as a 30 scale.

With these ends in view my invention consists in certain features of construction and combination of parts, as will be hereinafter described, and set forth in the claims.

35 In the accompanying drawings, Figure 1 is a side elevation of the combined truck and scale in position to receive a load. Fig. 2 is a top plan view. Fig. 3 is a side elevation, the parts being in position to weigh. Fig. 4 is a transverse vertical section on line 4 4 of Fig. 3. Fig. 5 is a detail view, partly in section, showing one of the suspending-links in the leg. Fig. 6 is a partial cross-section on line 6 6 of Fig. 3. Fig. 7 is a partial cross-section on line 7 7 of Fig. 4. Fig. 8 is a partial cross-section on line 8 8 of Fig. 4. Fig. 9 is a partial cross-section on line 9 9 of Fig. 3; and Fig. 10 is a detail view, partly in section, showing the attachment of the lever to 50 the standard-support at the front end of the truck.

The truck proper consists of a pair of side

rails, A, united by cross-beams a to form a stout frame-work, and terminating rearwardly in a pair of handles, a', and a pair of supporting-wheels, B, secured to the frame A a near the front end, as is usual. The ordinary lip, C, for the purpose of engaging the bottom of a box or truck to enable it to be tilted over onto the truck-frame, is also provided. 55

The wheels B are preferably mounted on stud-axles b, or on the end of an arch axle, in order to allow free space between the wheels below the truck-frame, for purposes which will hereinafter appear. 60

65 A skeleton frame, preferably rectangular in shape, and consisting of the side rails D, cross-ties d, legs E, and standard-bearings e, is constructed of such dimensions as to correspond with the width of the truck-frame, or substantially so, and has a length somewhat less than the truck-frame, exclusive of the handles, as shown. The exact length, width, and shape of the skeleton frame are not, however, essential; but that which is shown is found to 70 be desirable as far as experience has as yet demonstrated.

75 The legs E and standard-bearings e are preferably formed of cast metal, and are provided with recesses F and f, respectively, in which are suspended links G, the upper ends of the links being hung in eyes g, secured to or formed integral with the tops of the legs and standards, and the sides and front webs, e, of the legs and standards forming a housing for 80 the links.

To the lower ends of the links G are pivotally secured, on knife-edge bearings g', the ends of the branches h and i of two bifurcated levers, H and I. The levers H and I extend in opposite directions from their pivotal bearings and overlap each other, the lever H extending forwardly to a point about midway of the length of the truck-body, and the lever I extending rearwardly to a point between the legs E. The 90 lever I is re-enforced by a diagonal brace, i', connecting the branch and main portions of the lever. The main portions of said levers H and I are located to one side of the center of the skeleton frame, the lever H being below 95 and slightly to one side of the lever I, and the end of the lever H is connected loosely with the lever I by a link, K, as shown.

The front end of the skeleton frame is sup-

ported on a pair of truck-wheels, L, the ends or journals of which have bearings in the lower ends of the standards e, and the rear end upon easter-rollers l, journaled in the lower 5 ends of the legs E.

The truck proper is connected with the levers H and I by means of four depending arms, M, the lower ends of which have a pivotal connection with the branches h and i on 10 knife-edge bearings at points a short distance inwardly from the end bearings of the lever branches on the links.

The skeleton frame D d, &c., is further held in position beneath the truck-frame by means 15 of guides N, preferably four in number, two on each side. The upper ends of the guides are firmly secured to the side rails A, and their lower ends extend downwardly along the sides of the rails D and hook under the same, 20 as shown at n, Fig. 6, to limit the possible movement of the rails D away from the rails A.

The mechanism for balancing the truck on the levers and for ascertaining the weight of anything supported on the truck is constructed 25 as follows: To the under side of the cross-tie d, at the rear or handle end of the truck, depending brackets O and P are secured, or said brackets might be formed integral with the legs E or with the cross-ties d, or the cross-tie 30 d, brackets, and legs might be formed integral. The bracket O is conveniently inverted U-shaped, and a graduated beam, Q, to denote the different denominations of weight, is pivoted near one end in the lower ends of the 35 bracket O on knife-edge bearings. The opposite end of the bar Q projects through the loop of the bracket P, and a swinging stop, p, serves to lock the bar Q against an up-and-down movement in the loop of the bracket, as is 40 common in scales. To further provide against a longitudinal movement of the beam Q transversely of the truck when not in use to weigh, the end of the beam is curved, as shown at q, and when the stop p is turned down the beam 45 is securely fastened against such longitudinal movement, which, because of the curved end, must necessarily require the end of the beam to rise.

At a point a short distance from the pivotal 50 support of the beam, and on the opposite side of said pivot from the graduated portion of the beam, the end of the lever I is suspended by a link, R, resting on knife-edge bearings. A balancing-weight, S, is mounted on a bent 55 arm, s, secured to the short arm of the beam Q, and a poise, T, is mounted on the graduated portion and provided with the usual index-finger.

The lowermost points of the wheels L and 60 rollers l are intended to be equally distant from the top of the frame D d, &c., so that when the said wheels and rollers rest on a plain horizontal surface the frame D d, &c., will be horizontal, and the arms M, which support 65 the truck on the levers, are of such length that when the frame D d, &c., is horizontal the truck-frame itself will also be substantially

horizontal. Furthermore, the relative position of the wheels L and B is such that when the truck and skeleton frame carrying the levers are horizontal the lowermost parts of the wheels B will be slightly above the surface on which the wheels L stand, as shown in Fig. 3; but when the truck is tilted forwardly into position to be used as a truck, as shown in Fig. 7, the wheels L will be clear from the surface on which the wheels B rest.

When employed to weigh, the truck is lowered into a horizontal position, as shown in Fig. 3, and the stop p turned to set free the 80 end of the beam Q. The weight on the truck will tend to depress the levers H and I, and because of their connection the combined effect will be transmitted to the short arm of the beam Q and the weight ascertained by sliding the poise T along the graduated beam until the parts are in equilibrium, as is usual. The suspending-links will admit of the truck assuming a horizontal position, even though the frame D d be slightly out of horizontal. 90

Among the advantages secured by the present construction may be mentioned the freedom with which the truck may be moved either forward or backward, whether the handles be elevated or partly depressed, to suit either a 95 tall or short individual, the suspending-links and their housing in the skeleton legs and standards, the construction and location of the levers, and the means for preventing the displacement of the several parts.

It is obvious that a spring-balance, substantially like that shown in Patent No. 366,753, above referred to, might be employed in the place of the graduated bar to indicate the weight to a considerable degree of exactness, 105 and that slight changes might be resorted to in the form and arrangement of the several parts described without departing from the spirit and scope of my invention; hence I do not wish to limit myself strictly to the construction herein set forth; but,

Having thus fully described my invention, what I claim as new, and desire to secure by Letters Patent, is—

1. The combination, with a truck, of a supporting-frame, wheels mounted thereon, a system of levers fulcrumed on the said supporting-frame, arms connecting the truck with the levers, and weighing mechanism to indicate the pressure upon the levers, substantially as set 115 forth.

2. In combination, a supporting-frame, wheels mounted at its forward end, levers fulcrumed on the frame, a truck supported on the levers at points rearward of the truck-supporting wheels to throw the weight of the truck wholly on the levers when in a horizontal position, and weighing mechanism to indicate the pressure upon the levers, substantially as set forth.

3. In combination, a supporting-frame, wheels mounted thereon, levers fulcrumed in links depending from the frame, a truck connected with and supported upon the levers, and

weighing mechanism in engagement with the levers, substantially as set forth.

4. In combination, a supporting - frame, wheels mounted upon the forward end of the same, links depending from the frame, levers fulcrumed at their ends in the links, a truck connected with and supported upon the levers, and weighing mechanism in engagement with the said levers, substantially as set forth.

10 5. In combination, a supporting - frame with skeleton legs, depending links housed within the legs, levers fulcrumed on the links, a truck connected with the supporting frame and supported on the levers in a limited up-and-down 15 movement, and weighing mechanism in connection with the levers, substantially as set forth.

6. In combination, a supporting - frame, wheels mounted upon the same at its forward 2c end, a pair of levers fulcrumed on the frame and extending toward and overlapping each other along one side of the center of the frame, a loose connection between the levers, a truck connected with and supported upon the levers, 25 and a graduated beam suspended in one end of the frame and connected at one end with the levers, and provided at the opposite end with a poise, substantially as set forth.

7. In combination, the skeleton frame, the levers fulcrumed on the frame, the truck supported upon the levers, and the depending guides at the sides of the truck having a loose engagement with the skeleton frame to prevent its displacement, substantially as set forth.

8. The herein-described weighing mechanism as a support for a truck, consisting, essentially, of the skeleton frame, the skeleton legs or housings at the corners, the links housed in said legs, the levers fulcrumed in the links, the graduated beam fulcrumed in the frame 40 and connected with the said levers, a balance-adjusting weight attached to the graduated beam, a poise secured on the graduated portion of the beam, and a stop to lock the beam against displacement when not in use to weigh, 45 substantially as set forth.

In testimony whereof I have signed this specification in the presence of two subscribing witnesses.

EDWARD G. COLLINS.
